ABSTRACT OF THE DISCLOSURE

In order to overcome the drawbacks due to the quantization of the phase shifters associated to electronic scanning antennas of the so-called counter-rotative type, the phase-position law is modified and means are supplied which avoid the simultaneous jumps of the values of several phase shifters.

The present invention relates to electronic scanning antennae, comprising a network of radiating elements so supplied that they radiate a beam which moves as a function of time following a periodical law. This is in particular the case with the so-called "counter rotative" antennae, used on board of a satellite and supplied through networks of the type of a Butler matrix or more generally a Fourier transform matrix.

In all cases, the movement of the beam is effected by varying the phase shift between the successive inputs of the matrix; the desired phase shift is a function of the position number of the matrix input concerned and of the desired direction of the beam.

In practice, for technological reasons, the phase shifters used are such that the above phase shifts have only certain predetermined values in arithmetical progression. Such phase shifters are called "quantized" phase shifters. This results in a jerky rotation and in pointing errors. This drawback is particularly aggravated by the fact that, up to now, the direction of the systematic phase errors due to quantization was chosen according to a simple law by merely rounding off each phase value to the nearest quantized value, irrespective of any other considerations. It follows that, for certain desired positions of the beam, simultaneous phase jumps on several phase shifters tend to enhance the jerky nature of the movement of the beam and increase the pointing error.

It is an object of the invention to minimize the drawbacks caused by the quantization of the phase shifters.

To this end according to the invention, there is provided a method for improving the accuracy of the pointing of the beam radiated by an electronic scanning antenna of the type comprising a plurality of radiating elements arranged on a closed surface and a plurality of controlled quantized phase shifters respectively associated therewith, and wherein, the beam pointing direction undergoing a rotation as a predetermined function of time, the theoretical phase shift values introduced by said phase shifter are computed as predetermined functions of time, said method consisting in:

Modifying the theoretical values of said phase shifts so as to accelerate or delay selectively the beam rotation with respect to said predetermined rotation;

Controlling the rounding off of the phase value due to the quantized operation of the phase shifter in such a manner that only the value of one phase shifter is changed at a time.

For a better understanding of the invention and to show how the same may be carried into effect reference will be made to the drawings accompanying the following description and in which:

FIG. 1 is a basic diagram of a conventional antenna to which the invention is applicable;

FIG. 2 is a basic diagram of an antenna improved according to the invention;

FIGS. 3, 4 and 5 are explanatory diagrams; and FIGS. 6 and 7 show details of the diagram of FIG. 2.

For the sake of clarity, the invention will be described with reference to the particular case of an antenna placed on a stationary satellite stabilized by rotation. The direction of the beam will therefore coincide with the direction of the center of the earth or form a fixed angle therewith. The beam must therefore be rotated relative to the satellite with a uniform speed equal to the rotation speed of the satellite, but in the opposite direction.

The general case of an antenna with periodic scanning will be derived from this particular case, by replacing the linear variations of the phase shifts by variations following some other law.

The known antenna shown in FIG. 1 is formed by radiating elements, A_1 to A_n , arranged in a circle around the satellite. The direction of the maximum radiation axis rotates about the axis of the circle in the plane thereof or making a constant angle therewith. The rotation of the beam is obtained, as is well known, by interposing between the input terminal T of the system and the radiating elements a circuit, known per se, comprising a power divider D, variable phase shifters Ph_1 to Ph_n and a Fourier transform matrix B with n entries and n outputs. As is known, to a linear and continuous variation of the phase of the phase shifters corresponds a gradual displacement of the illuminated radiating elements along the elements A_1 to A_n and therefore a uniform rotation of the beam. The phase shifts necessary at each input of the matrix are linear functions of the number determining the position of the input and of the angle of rotation desired. In practice, the phase shifters Ph_1 to Ph_n are quantized. The control of the value of the quantized phase shift caused by the phase shifters Ph_i ($i=1, 2 \dots n$) is effected by means of a phase calculator 3, a calculator of the rounded-off values 4 and an arrangement 5 for the control of the phase shifters.

The arrangement 3 receives the indication of the desired pointing angle θ_o , θ_o being the angle between the beam and a reference direction in the plane of the radiating elements, if the axis of the beam is within this plane, or the angle made by the projection of the beam with this reference direction, if the beam rotates whilst forming a constant angle with the axis of the circule along which the sources are positioned.

The input which receives the signal θ_o is connected, for example, to a known device 6 which senses the position of the satellite. The calculator 3 delivers at its n outputs the theoretical values of the phases of the n phase shifters. These values are compared with different quantized levels in the rounding off calculator 4 which determines the orders to be given to the different phase shifters. These orders are translated, for example, into control voltages in the case, which is the most common, of voltage controlled phase shifters, in the arrangement 5 which forms the phase shifter control signals.

The rounding-off calculator is, for example, a simple comparator, for example a flip-flop type comparator, which involves the drawbacks mentioned above.

For the sake of clarity, the n connections between the arrangements 3, 4 and 5, are shown only as two lines but it is to be understood that, for each phase shifter, there is effected a phase computation and a rounding-off computation; a control voltage is thus provided.

The antenna improved according to the invention, which is shown in FIG. 2, comprises a modified circuit for determining the theoretical phase and the quantized phase which avoids simultaneous phase "jumps," on a plu-

rality of phase shifters, i.e., substantial jerks, and on the other hand accelerates or delays the beam rotation so that it comes nearest the desired position.

According to the invention, this circuit comprises:

An arrangement 7 for correcting the law $\varphi(\theta_0)$, which defines the phase as a function of the desired pointing direction θ_0 , which is inserted between the signal θ_0 input and the phase calculator 3; and

An arrangement for determining the rounded off value, which is substituted for the calculator 4, and which comprises a test circuit with a source of random signals 9.

The arrangement 7 is, for example, a memory in which is recorded a set of values θ , corresponding respectively to a set of values θ_0 , such that $\varphi(\theta)=\varphi_1(\theta_0)$, where $\varphi(\theta)$ is the phase law of the calculator 3 of FIG. 1 and $\varphi_1(\theta_0)$ is the corrected law, which results in a pointing direction $\theta+d\theta$, which is the desired direction.

An embodiment of the arrangement 7 is described further below.

The rounding off circuit is constructed with a view to avoiding the simultaneous variation on several phase shifters.

To sum up, the circuit for correcting the phase law makes it possible to compensate for the average pointing error with periodical variation, by accelerating or delaying the rotation of the beam and the circuit for determining the direction of the rounding off makes it possible to compensate for quick variations of this error.

The diagrams in FIGS. 3, 4 and 5 explain the advantages of the system according to the invention.

FIG. 3 shows in solid lines the variation of the phase φ , which is plotted along the ordinates as a function of the position p of the phase shifter concerned, which positions are plotted along the abscissae: for a given value θ_0 . The theoretical variation is linear (straight solid line).

Due to the quantization, the effectively followed phase law is that shown in dashed lines, it is stepwise and Φ represents the quantization step.

The circuit according to the invention for determining the rounding off direction makes it possible both to reduce the pointing error caused by the rounding off operation and to avoid sudden variations in the direction of the radiation axis by preventing simultaneous jumps of several phase shifters.

To this end, the theoretical phase is compared with odd multiples of $\Phi/2$; if it is equal to one of them, the choice of the direction of the rounding off is determined from a random voltage ϵ_p , supplied by a noise generator associated with each phase shifter. According to whether this voltage is lower or higher than a threshold value, the rounding off is effected to the lower or higher quantized value.

On the other hand, all other things being equal, due to the quantization, for a linear variation of the phase as a function of θ_0 , a pointing error $d\theta_0$ is obtained which is a function of θ_0 , such as shown, for example, at 41 in FIG. 4.

By substituting for the linear law $\varphi(\theta_0)$ a different law $\varphi_1(\theta_0)$, it is possible to accelerate or to delay the rotation according to whether $d\theta_0$ is negative or positive, and to obtain, for example, a corrected law $d\theta_0(\theta_0)$, shown at 42 in FIG. 4.

FIGS. 6 and 7 are non-limiting examples of embodiments of the arrangements 7 and 8.

For the sake of clarity, it will be assumed that, in the absence of any readjustment of the beam directions according to the invention, the pointing error $d\theta$ is a sinusoidal function of the period $2\pi/n$ of the angle θ .

Disregarding rapid changes of $d\theta$, caused by jumps of the value Φ of the phase shifters and minimized by the rounding off determination circuits, the mean error $d\theta$ has the form $d\theta=K \sin n\theta$.

The problem is therefore to determine which value of θ to select for so calculating the phases that the beam

is pointed in a desired direction θ_0 : the value of θ is the solution of the equation

$$\theta_0=\theta+k \sin n\theta \quad (1)$$

which can be solved graphically, as shown in FIG. 5.

The arrangement 7 may comprise a computer which solves the equation 1 and delivers for each input signal θ_0 the value θ to the phase calculator 3.

More simply, the arrangement 7 may consist, as shown in FIG. 6, of a memory 71 which records a certain number of values θ , corresponding to predetermined values of θ_0 , and of an arithmetic interpolation calculator 72 which solves the equation

$$\theta=\theta'-(\theta-\theta'') \frac{\theta_0-\theta'_0}{\theta_0-\theta''_0}$$

where θ_0 is the exact value indicated by the position sensing device 6, θ'_0 and θ''_0 are the two predetermined values on both sides of θ_0 , and θ' and θ'' are the values of θ corresponding to θ'_0 and θ''_0 .

The rounding off determination circuit 8 may be a digital or an analogue circuit.

FIG. 7 shows, by way of non limiting example, a first embodiment: the theoretical phase φ_{th} , delivered by the calculator 3, is compared in a multiple level comparator 81 with odd multiples of the quantization step, i.e.

$$\left(2k+1\right)\frac{\Phi}{2}$$

At the output of the comparator 81 appears a signal "1" if φ_{th} is equal to one of these levels, and no signal if not. This output is connected to control inputs of two gates 821 and 822, the first of which is normally open, i.e., remains open in the absence of any control signal, and the second is normally closed. The output of the calculator is also connected to the signal inputs of these two gates. The output of the gate 821 is connected to a rounding off calculator 84, identical to the arrangement 4 of FIG. 1 which supplies the value of the quantized phase nearest to φ_{th} .

The output of the gate 822 is connected in parallel to the inputs of two gates 831 and 832 which operate in opposition.

The random voltage ϵ_p , supplied for example by the noise generator 9, is compared at 810 with a threshold voltage V_s and, according to the result of the comparison, there appears at the output of 810 a signal "1" or "0".

This output is connected to the control inputs of the gates 831 and 832. If $\epsilon_p < V_s$, the output signal of 810 is "0," the gate 831 is open and the signal corresponding to φ_{th} arrives at the device 841 which calculates the phase rounded off to the lower quantized value. If on the other hand $\epsilon_p > V_s$, the signal corresponding to φ_{th} arrives at the calculator 842 which calculates the phase rounded off to the upper quantized value. The arrangements 84, 841, 842, of which only one is in use at a time, feed the control arrangement 5.

Of course, there are as many voltages ϵ_p and associated circuits as there are phase shifters in use.

Various modifications to the circuits described may be devised. For example, the gates 822, 831 and 832 may be combined to form a single device with multiple control inputs, the essential point being that, the rule for calculating φ_{th} takes into account the fact that quantized phase shifters are used, and that logical circuit inhibiting the simultaneous jumps of the phase φ_p are used.

Although the invention has been described in the foregoing with special reference to the case of an antenna mounted on a satellite, where the angle θ_0 is determined by a position sensing device, the invention may be used wherever the pointing angle is a periodical function.

Of course, the invention is not limited to the embodiment described and shown which was given solely by way of example.

What is claimed is:

1. A method for improving the accuracy of the pointing of the beam radiated by an electronic scanning antenna of the type comprising a plurality of radiating elements arranged on a closed surface and a plurality of controlled quantized phase shifters respectively associated therewith, and wherein, the beam pointing direction undergoing a rotation as a predetermined function of time, the theoretical phase shift values introduced by said phase shifter are computed as predetermined functions of time, 10 said method consisting in:

modifying the theoretical values of said phase shifts so as to accelerate or delay selectively the beam rotation with respect to said predetermined rotation;

controlling the rounding off of the phase values due to 15 the quantized operation of the phase shifter in such a manner that only the value of one phase shifter is changed at a time.

2. An improvement to electronic scanning antennas of the type comprising a plurality of n radiating elements 20 numbered 1 to n , arranged on a closed surface, a plurality of n controlled quantized phase shifters numbered 1 to n respectively associated therewith having respective control inputs coupled to a control circuit comprising in series a phase calculator computing n theoretical phase 25 shift values according to a theoretical law, and n rounding off means which round off respectively said n phase shift values to the nearest quantized values, said improvement consisting of means connected to said calculator for modifying the law according to which said phase shift 30 values are computed, of n test circuits respectively numbered 1 to n having respective control inputs and of n random signal generators respectively numbered 1 to n coupled respectively to said n test circuits, said n test circuits being substituted respectively for said n rounding off means, the test circuit numbered i , where $i=1, 2 \dots n$ operating the rounding off of the phase shift 35 value of the phase shifter numbered i to an inferior or a superior value according to whether the signal supplied by

said random signal generator numbered i is lower or higher than a predetermined value.

3. An improvement according to claim 2, wherein said modifying means comprises a memory and an interpolation calculator inserted in series at the input of said phase calculator.

4. An improvement according to claim 2, wherein each said test circuit comprises a multiple level comparator having an input coupled to said phase calculator and an output; a first and a second gate, operating in opposition, having respective signal inputs coupled to said phase calculator, respective control inputs coupled to said comparator output and a first and a second output; a rounding off calculator which rounds off said phase shift to the nearest value, having an input coupled to said first output and an output coupled to said control circuit; a threshold comparator having an input coupled to said random signal generator and an output; a third and a fourth gate operating in opposition having respective signal inputs coupled to said second output, respective control inputs coupled to said threshold comparator output and respectively a third and a fourth output; and a rounding off calculator rounding off to the nearest lower value and a rounding off calculator rounding off to the nearest higher value having respective inputs coupled respectively to said third and fourth outputs and respective outputs coupled to said control circuit.
